THREAD COVERING APPARATUS

Sterling W. Alderfer, Akron, Ohio, assignor to
 The Firestone Tire & Rubber Company, Akron,
 Ohio, a corporation of Ohio

Application July 28, 1938, Serial No. 221,785

8 Claims. (Cl. 57—18)

This invention relates to improvements in thread covering apparatus, and more especially to apparatus for covering a core strand with a winding of cotton, silk, rayon, or the like.

In prior types of elastic thread covering apparatus, the cover thread is taken from a rotating spool, or bobbin, through a guide loop, or eyelet in the end of a free flyer mounted upon a flange on the end of the bobbin and the thread is wound around the core thread as the latter is slowly moved along the axis of the rotating bobbin. It is necessary to wind the covering thread upon the core under tension in order to secure uniform covering and the tension causes the cover thread to bind against the guide loop as it is drawn therethrough. This produces a momentarily high frictional contact between the guide loop and the cover thread when the machine is started and frequently results in breaking the cover thread. The frictional engagement between the thread and the guide loop also produces a non-uniform cover of the core thread, or strand when the apparatus is started or stopped.

The main object of this invention is to overcome the foregoing and other disadvantages of prior types of thread covering apparatus and to eliminate the breakage of the cover thread at the time of starting or stopping the apparatus.

Further objects and advantages of this invention will be made evident by the following specification.

The present invention broadly comprises carrying the tensioned cover thread upon two spaced guide plates, or discs, which are associated with one end of the bobbin. The discs are provided with rounded edges on which the thread drawn from the bobbin bears as it passes to the core strand. A flyer is freely carried between the spaced discs and is provided with a bent end which engages with and circumferentially positions the covering thread on the discs as it is drawn from the bobbin. Thus, the flyer has no radially directed load thereon and is free for rotation relative to the bobbin whereby no appreciable force is necessary to start or stop the flyer relative to the bobbin.

In the accompanying drawing:

Figure 1 is an elevation, partly in section, of an embodiment of the invention;

Figure 2 is a detail vertical section of a portion of the apparatus of Figure 1; and

Figure 3 is a horizontal cross section taken on line 3—3 of Figure 1.

Referring specifically to the drawing, the bob-

bin 10, carrying a cover thread 11 of cotton, silk, rayon or the like thereon, is rotatably mounted on a pulley 12 which engages with a belt 13 driven by any suitable means (not shown). A core strand 14, which may be made from any suitable material, either elastic or inelastic, extends through the axial bores of the pulley 12 and bobbin 10. A spindle 15, extending axially from the bobbin, is secured to the bobbin 10 at one end by a lock nut 16. The core strand 14 extends through the axis of the spindle 15 which has an annular flange 20, having rounded edges, formed thereon adjacent its end. Two discs, or guide plates, 17 and 18 are carried by the spindle 15 in spaced relation immediately adjacent the bobbin 10. The guide plates 17 and 18 extend radially beyond the edges of the bobbin 10 and have their edges curved, or flanged in towards each other to provide smoothly curved outer surfaces on both of the guide plates. A guide plate spacer 19 is carried by the spindle 15 to space the guide plates, as desired. Figure 1 shows how the cover thread 11 is drawn over the guide plates in passing from the bobbin to the core strand.

A flyer 21 is rotatively carried between the guide plates 17 and 18 by a member 22, which preferably is made from fiber or other light material, and which loosely engages with the guide plate spacer. Figure 3 shows that the end of the flyer 21 is bent to substantially L-shape to provide means for engaging with the cover thread 11. It will be observed that the flyer 21 engages with the cover thread but does not radially position it, this being done by the edge of the guide plates.

Upon rotation of the bobbin 10 around the core strand, relative rotation is produced between the flyer 21 and the guide plates, carried by the bobbin, due to the wind resistance of the flyer and to the drag exerted thereon by the cover thread 11. The flyer offers sufficient resistance to withdrawal of cover thread from the bobbin to maintain it tensioned as it is wrapped around the core strand and this aids in producing a high quality product. Preferably means, such as a washer 23, is placed upon the member 22 to hold it adjacent the lower guide plate 18 and to increase slightly the resistance of the flyer to rotation. This prevents the flyer and the member 22 from moving upwardly relative to the spindle when the bobbin is rotating.

In accordance with the patent statutes, I have illustrated and described the structure and mode of operation of an embodiment of the invention. However, it will be understood that various modi-

fications can be made without departing from the scope of the invention as defined in the appended claims.

What is claimed is:

5. 1. In apparatus for covering a core strand, a bobbin having thread wrapped thereon and having a bore through which the core strand extends, mounting means for said bobbin, means for rotating said bobbin, a spindle secured to and 10 extending axially from said bobbin, said spindle having an annular flange formed thereon adjacent its end to guide the thread onto the core strand, two discs carried by said spindle and protruding radially beyond the edges of said bobbin, 15 said discs being spaced from each other, a flyer loosely engaged with said spindle between said discs and being supported by the lower of said discs, said flyer terminating in an L-shaped arm which extends beyond said discs, and means 20 bearing upon said flyer to hold it adjacent the lower of said discs, rotation of said bobbin forcing the thread against the arm of said flyer to tension the thread which is drawn over the curved edges of said discs and led to the core 25 strand over said annular flange.
2. In apparatus for covering a core strand, a bobbin having thread wrapped thereon and having a bore through which the core strand extends, means for rotating said bobbin, a spindle 30 secured to and extending axially from said bobbin, said spindle having a rounded annular flange formed thereon adjacent its end, two discs carried by said spindle and protruding beyond the edges of said bobbin, said discs being spaced from 35 each other and having their edges smoothly curved inwardly towards each other, and a flyer loosely engaged with said spindle between said discs and being supported by the lower of said discs, said flyer terminating in an L-shaped 40 arm which extends beyond said discs and engages with said thread as it is led to the core strand, rotation of said bobbin forcing said thread against the arm of said flyer to tension it whereby said thread bears upon the curved 45 edges of said discs and said annular flange in being wound around the core strand.
3. In thread covering apparatus, a rotatable bobbin having thread thereon, two spaced discs 50 associated with said bobbin at one end thereof and extending out radially beyond said bobbin, said discs having their outer edges rounded off, a spindle having an annular flange adjacent the end thereof extending axially from said discs, and a flyer having a bent end carried between 55 said discs and engaging with but not radially positioning the thread drawn from said bobbin by rotation thereof, said thread being tensioned by the drag of said flyer and bearing on the edges of said discs and said annular flange whereby

they carry the radial force produced in tensioning the thread.

4. In thread covering apparatus, a rotatable bobbin having thread thereon, two spaced discs associated with said bobbin at one end thereof and extending out radially beyond said bobbin, 5 said discs having their outer edges rounded off, a spindle having an annular flange adjacent the end thereof extending axially out from said discs, and a freely mounted flyer carried between said 10 discs and having a bent end that circumferentially positions the thread drawn from said bobbin by rotation thereof upon said discs, said flyer being free to rotate relative to said bobbin and to the thread. 15

5. In thread covering apparatus, a rotatable bobbin having thread thereon, two spaced discs associated with said bobbin at one end thereof and extending out radially beyond said bobbin, 20 and a freely mounted flyer carried between said discs and circumferentially positioning the thread drawn from said bobbin by rotation thereof upon said discs, said thread bearing on the edges of said discs which carry the radial force produced in tensioning the thread. 25

6. In thread covering apparatus, a rotatable bobbin having thread thereon, means associated with said bobbin at one end thereof and extending out radially beyond said bobbin for supporting the thread drawn from said bobbin, and a 30 flyer loosely associated with said means for circumferentially positioning the thread drawn from said bobbin by rotation of said flyer with respect to said bobbin, said flyer being engaged with the thread only on forward movement of the thread. 35

7. In thread twisting apparatus, a rotatable bobbin having thread thereon, two spaced discs associated with said bobbin at one end thereof and extending out radially beyond said bobbin, 40 a spindle having an annular flange adjacent the end thereof extending axially out from said discs, and a flyer carried between said discs and having a bent end that circumferentially positions the thread drawn from said bobbin by rotation thereof upon said discs, said flyer being free to rotate 45 relative to said bobbin and to the thread.

8. In thread covering or twisting apparatus, the combination of a positively driven spindle, a bobbin having thread thereon carried by said spindle, disc means associated with one end of 50 said bobbin and extending radially outwardly therefrom to support the thread drawn from said bobbin, and a freely rotatable flyer journaled upon the axis of said bobbin and extending outwardly from said disc means to engage with and produce a drag on thread drawn from said bobbin. 55
